UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed December 17, 1923, Serial No. 681,046. Renewed July 27, 1927.

This invention relates to improvements in mining machines and more particularly to coal cutting machines which are permanently mounted on a wheel truck and movable angularly thereon during the cutting operation.

The principal object of this invention is to provide an improved construction of tilting mechanism whereby the cutter arm may be presented at various angles deviating 10 from the coating threaded members with reference to the truck wheels.

The invention may be best understood by reference to the accompanying drawings, in which:

15 Figure 1 is a view in side elevation of a mining machine constructed in accordance with my invention;

Figure 2 is a longitudinal section of the machine shown in Figure 1;

20 Figure 3 is a plan view of the machine with parts broken away to show the tilting mechanism;

Figure 4 is a view in part section taken on line 4—4 of Figure 1;

25 Figure 5 is a view taken on line 5—5 of Figure 1 with parts broken away to show the adjusting mechanism associated therewith;

Figure 6 is a detail of the adjusting mechanism associated with the rear axle.

Referring now to the details shown in the drawings, I have shown my invention as applied to a mining machine of the overcutting or slabbing type having as its principal elements a forwardly projecting cutter arm 10 supported on a turntable 11 mounted for pivotal movement on a main frame 12, which frame is supported by the axles 13 and 14 having supporting wheels 15, 15 and 16, 16 respectively. Means are also provided for adjusting the vertical position of the cutter arm on its support, but these and other details of construction need not be described, as they form no part of the present invention.

45 Mining machines of the general type herein illustrated have heretofore been provided with various means for tilting the pivotal axis of the cutter arm 10 so that the latter may be swung in varying angular planes respective to the supporting wheels and axles. This adjustment is found advisable in practice for several reasons, chief among them being the variation in pitch of coal seams

which it is desired to cut. Heretofore it has been the usual practice to mount the main frame substantially rigid with respect to the supporting wheels and interpose a tilting adjustment between the main frame and the cutter arm. The principal feature of the present invention is to provide a tilting mechanism interposed between the main frame and the supporting wheels by means of which the position of the entire main frame and the cutter arm together with the mechanism carried therewith may be tilted both on longitudinal and transverse axes relative to the supporting wheels and axles.

55 In carrying out my invention it will be seen that the rear axle 13 is journaled in a bolster 20, which in the form shown is substantially hollow and extends the full length of the axle between its supporting wheels 15, 15. Centrally of this bolster is provided a pair of oppositely disposed longitudinally 60 extending bearings 21, 22, in which are mounted shafts 23 and 24 in alignment with each other. These shafts project outwardly beyond their respective bearings and are journaled in trunnions 25 and 26 extending 65 downwardly and forming a part of the main frame 12 of the machine. By means of the trunnion support just described it will be seen that the entire mechanism may be tilted upon a longitudinal axis relative to the 70 rear axle 13. Adjustment of this tilting movement is provided by suitable mechanism such as shown in Figures 3, 5 and 6. Integral with the bolster 20 is a projecting arm 27 herein extending forwardly and having at its forward end a pair of trunnions 30, 31 in which are supported a pair of pins 32, 33, arranged on a longitudinal axis connected to an enlarged socket member 28. A screw member 29 is threaded in the socket member 75 28, said screw member being rotatably mounted on a vertically disposed pin 34. This pin is pivotally connected to the main frame 12 by means of a cross pin 35 secured 80 in an eye 36 at the upper end of said vertical pin and bearing in a pair of lugs 37, 37 formed integral with a supporting plate 39 secured to the main frame, (see Figures 5 and 6). A retaining nut 41 is threaded on the lower end of the vertical pin 34 to retain the threaded member 29 thereon. Suitable means are provided for rotating the 85 threaded member respective to the socket 28

90

95

100

105

which means may comprise a plurality of laterally extending projections 42, 42, having sockets 43, 43 therein for receiving a turning bar or handle of the usual kind. 5 From the above description of the adjusting mechanism it will be seen that the main frame may be tilted relative to the rear axle by screwing the threaded member up or down in the socket 28, the pivotal connections of the coacting threaded members with their respective elements affording compensation for the slight variations in the normal parallel relationship of the main frame and the axle bolster. 15 The front axle 14 is also mounted in a bolster 45 extending between the supporting wheels 16, 16 and provided with a trunnion connection in alignment with the trunnion connection of the rear axle 13 so as to permit the main frame to tilt on a common longitudinal axis when the longitudinal tilting adjustment is manipulated. This trunnion mechanism on the front axle 14 comprises a pair of pins 46, 46 extending between supporting members 47, 47 integral with the front bolster 45 and having a socket 48 spanning the axle and provided with arms 49, 49 bearing on said pins. (See Figures 2 and 4.) The forward axle is also provided 20 with means for tilting the main frame on a transverse axis which in the present construction comprises a threaded screw member 50 carried by the socket 48 before described, and extending upwardly therefrom into threaded engagement with a socket member 51 rotatably mounted in a downwardly extending boss 52 formed integral with the main frame. The turning member is provided with means for rotating the same 25 which may comprise a plurality of projecting arms having sockets 53, 53 therein for engagement by a turning bar or handle in a similar manner to that already described in connection with the longitudinal adjusting 30 mechanism.

It will be observed that the raising or lowering of the main frame relative to the front axle causes the entire frame to be tilted upon a transverse axis with the rear axle and supporting wheels forming the fulcrum. 35

The adjusting devices relative to the two axles provide a simple and efficient means for tilting the cutter arm either on a transverse or a longitudinal axis, all of the mechanisms being compactly located beneath the main frame so as to require a minimum overall height of the entire apparatus. The front axle is free to rock on a longitudinal axis respective to the rear axle thereby affording relative flexibility of the axles when traveling over uneven track. 40

Although I have shown and described one form in which my invention may be embodied, it will be understood that the ar-

rangement and construction of the various parts may be altered without departing from the spirit and scope thereof. Therefore I do not wish to be understood as limiting myself to the particular construction herein illustrated, except as it may be specifically limited in the appended claims. 70

I claim as my invention:

1. In a mining machine provided with a pair of supporting axles having wheels thereon, and a main frame above said axles carrying a turntable, a cutting element supported on said turntable to cut across the front of said main frame, the combination of tilting mechanisms interposed between each of said axles and said main frame and below said turntable to permit independent relative movement of said axles and said frame on transverse and longitudinal axes. 80

2. In a mining machine provided with a pair of supporting axles having wheels thereon, and a main frame above said axles carrying a turntable, a cutting element supported on said turntable to cut across the front of said main frame, the combination of tilting mechanisms interposed between each of said axles and said main frame and below said turntable to permit independent relative movement of said axles and said frame on transverse and longitudinal axes, and means connected with one of said axles for controlling the tilting movement on a longitudinal axis. 90

3. In a mining machine provided with a pair of supporting axles having wheels thereon, and a main frame above said axles carrying a turntable, a cutting element supported on said turntable to cut across the front of said main frame, the combination of tilting mechanisms interposed between each of said axles and said main frame and below said turntable to permit independent relative movement of said axles and said frame on transverse and longitudinal axes, and means connected with one of said axles for controlling the tilting movement about the axis of the other axle. 100

4. In a mining machine provided with a pair of supporting axles having wheels thereon, and a main frame above said axles carrying a cutting element movable to cut across the front of said frame, the combination of tilting mechanisms interposed between each of said axles and said main frame to permit independent relative movement of said axles and said frame on transverse and longitudinal axes, and a single controlling means connected with one of said axles for controlling the tilting movement on a longitudinal axis and a second controlling means connected with the other of said axles for controlling the tilting movement about the axis of the first named axle. 115

5. In a mining machine provided with a pair of supporting axles having wheels 130

- thereon, and a main frame above said axles carrying a cutting element movable to cut across the front of said frame, the combination of tilting mechanisms interposed between each of said axles and said main frame to permit independent relative movement of said axles and said frame on transverse and longitudinal axes, and a single controlling means connected with the rear axle for controlling the tilting movement on a longitudinal axis and a second controlling means connected with the front axle for controlling the tilting movement on a transverse axis.
6. In a mining machine provided with a pair of supporting axles having wheels thereon, and a main frame above said axles carrying a cutting element movable to cut across the front of said frame, the combination of tilting mechanisms interposed between each of said axles and said main frame to permit independent relative movement of said axles and said frame on transverse and longitudinal axes, and a single controlling means disposed centrally of the front axle and beneath the main frame for controlling the tilting movement on a transverse axis.
7. In a mining machine provided with a pair of supporting axles having wheels thereon, and a main frame above said axles carrying a cutting element movable to cut across the front of said frame, the combination of tilting mechanisms interposed between each of said axles and said main frame and within the boundaries of the latter to permit independent relative movement of said axles and said frame on transverse and longitudinal axes, and means disposed adjacent one side of the rear axle to control the tilting movement on a longitudinal axis.
- 40 8. In a mining machine, a main frame, a cutting element supported thereby, movable to cut across the front of said frame a pair of supporting axles and wheels mounted within the boundaries of the main frame having independent bearing means therefor, means pivotally connecting each of said bearing means with said main frame on a longitudinal axis, and controlling means interposed between one of said bearing means and said main frame.
- 45 9. In a mining machine, a main frame, a cutting element supported thereby, a pair of supporting axles and wheels mounted below the main frame having independent bearing means therefor, means pivotally connecting each of said bearing means with said main frame on a longitudinal axis, and controlling means interposed eccentrically of said longitudinal axis between one of said bearing means and said main frame.
- 50 10. In a mining machine, a main frame, a cutting element supported thereby, a pair of supporting axles and wheels mounted below the main frame having independent bearing means therefor, means pivotally connecting each of said bearing means with said main frame on a longitudinal axis, controlling means interposed eccentrically of said longitudinal axis between the bearing means for one of said axles and said main frame, and other controlling means interposed between the pivotal connection on the other of said axles and the main frame for raising and lowering said main frame bodily with respect to said axle.
- 55 11. In a mining machine, a main frame, a cutting element supported thereby, a pair of supporting axles and wheels mounted below the main frame having independent bearing means therefor, means pivotally connecting each of said bearing means with said main frame on a longitudinal axis, controlling means interposed eccentrically of said longitudinal axis between the bearing means for the rear axle and said main frame, and other controlling means interposed between the pivotal connection on the front axle and said main frame for raising and lowering the main frame bodily with respect to said axle.
- 60 12. In a mining machine, a main frame, a cutting element supported thereby, a pair of supporting axles and wheels mounted below the main frame having independent bearing means therefor, means pivotally connecting each of said bearing means with said main frame on a longitudinal axis, screw devices interposed eccentrically of said longitudinal axis between the bearing means for one of said axles and said main frame, and other screw devices interposed between the pivotal connection on the other of said axles and the main frame for raising and lowering said main frame bodily with respect to said axle.
- 65 13. In a mining machine, a main frame, a cutting element supported thereby, a pair of supporting axles and wheels mounted below the main frame having independent bearing means therefor, means pivotally connecting each of said bearing means with said main frame on a longitudinal axis, screw devices interposed eccentrically of said longitudinal axis between the bearing means for the rear axle and said main frame, and other screw devices interposed between the pivotal connection on the front axle and said main frame for raising and lowering the main frame bodily with respect to said axle.
- 70 14. In a mining machine, a main frame, a turntable, a cutting element supported thereby, a pair of supporting axles and wheels mounted below the main frame having independent bearing means therefor, means pivotally connecting each of said bearing means with said main frame on a longitudinal axis, and screw devices interposed between one of said bearing means and said main frame beneath said turntable.

15. In a mining machine, a main frame, a turntable, a cutting element supported thereby, a pair of supporting axles and wheels mounted below the main frame having independent bearing means therefor, means pivotally connecting each of said bearing means with said main frame on a longitudinal axis, and screw devices interposed eccentrically of said longitudinal axis between 10 one of said bearing means and said main frame beneath said turntable.

16. In a mining machine, a main frame, a turntable, a cutting element supported thereby, a pair of supporting axles and wheels mounted below the main frame having independent bearing means therefor, means pivotally connecting each of said bearing means with said main frame on a longitudinal axis, screw devices interposed between 15 one of said bearing means and said main frame, pivotal connections between said screw devices and bearing means and other screw devices interposed between 20 one of said bearing means and said main frame, pivotal connections between said screw devices and bearing means and other screw devices interposed between said screw de-

vices and said main frame beneath said turntable.

17. In a mining machine, a main frame, a turntable, a cutting element supported thereby, a pair of supporting axles and wheels mounted below the main frame having independent bearing means therefor, means pivotally connecting each of said bearing means with said main frame on a longitudinal axis, screw devices interposed between the rear bearing means and said main frame, pivotal 30 connections between said screw devices and the rear bearing means, other pivotal connections between said screw devices and said main frame, and other screw devices interposed between the pivotal connection of the front bearing means and said main frame all 35 of said screw devices being located beneath said turntable.

Signed at Chicago, in the county of Cook and State of Illinois, this 13th day of December, A. D. 1923.

THOMAS E. PRAY.
